(57) **CLAIM**

The ornamental design for a hearing device, as shown and described.

DESCRIPTION

FIG. 1 is a front right perspective view of a hearing device in accordance with an embodiment of the claimed design; FIG. 2 is a front elevation view of the design of FIG. 1; FIG. 3 is a rear elevation view of the design of FIG. 1; FIG. 4 is a left side elevation view of the design of FIG. 1; FIG. 5 is a right side elevation view of the design of FIG. 1; FIG. 6 is a top plan view of the design of FIG. 1; FIG. 7 is a bottom plan view of the design of FIG. 1; FIG. 8 is a front right perspective view of a hearing device in accordance with another embodiment of the claimed design;

FIG. 9 is a front elevation view of the design of FIG. 8; FIG. 10 is a rear elevation view of the design of FIG. 8; FIG. 11 is a left side elevation view of the design of FIG. 8; FIG. 12 is a right side elevation view of the design of FIG. 8;

FIG. 13 is a top plan view of the design of FIG. 8; and, FIG. 14 is a bottom plan view of the design of FIG. 8. The ornamental designs also include the mirror images of the embodiments illustrated in FIGS. 1-14.

The dash-dash broken lines in the figures represent unclaimed subject matter and form no part of the claimed design.

The dot-dash broken lines in the figures immediately adjacent the solid lines represent a boundary between claimed and unclaimed subject matter and form no part of the claimed design.

The labels used herein to describe orientation (e.g., top, bottom, left, right) are merely for reference and are not intended to limit the interpretation of the design.

The broken lines depict portions of the hearing device that form no part of the claimed design.

1 Claim, 14 Drawing Sheets
